UNITED STATES PATENT OFFICE.

HENRY L. GUENTHER, OF LOS ANGELES, CALIFORNIA.

CAN-CAPPING MACHINE.

Application filed July 8, 1925. Serial No. 42,237.

This invention relates to can making machinery and particularly pertains to can and cap feeding and timing mechanism.

In the performance of can making machinery, and particularly in the delivery of filled cans and their caps to can double seaming machines, considerable difficulty has arisen in rapidly spacing, timing and feeding cans to can seaming means in synchronism with the operation thereof and without disturbing the contents of the cans to such an extent that slop or spill will be produced. It is the principal object of the present invention, therefore, to provide means for taking cans as they flow along the can chute, separate the cans without violent action or jar, and then delivering said cans in timed succession to cap feed means, where each can is given a cap, and where the respective cans and caps are fed coincidentally to the seaming mechanism, all of which progressive movement of the cans is effected at a gradually accelerating rate of speed with the incidental action that the cap feed will remain inoperative when no can is present to receive a cap, and that the entire feed mechanism will be rendered inoperative when there is no cap to be placed on a can.

The present invention contemplates the use of an initial rotary spacing device by which cans are delivered to a rotary can timing and accelerating device, transferring the cans to a second can and can cap accelerating device adapted to carry the cans and their associated caps to the first operation mechanism of a double seaming machine.

The invention is illustrated by way of example in the accompanying drawings, in which:

Fig. 1 is a view in side elevation showing the complete mechanism with which the present invention is concerned.

Fig. 2 is a fragmentary view in vertical section showing means for actuating one of the initial can timing and accelerating arms.

Fig. 3 is a view in plan showing the assembled mechanism as disclosed in Fig. 1.

Fig. 4 is an enlarged fragmentary view in plan showing the construction of the "no cap, no can" safety device.

Fig. 5 is an enlarged view in plan showing parts of the structure with other parts

removed, while indicating the construction of the "no can, no cap" safety device.

Fig. 6 is an enlarged view in central vertical section showing the "no cap, no can" operating mechanism.

Fig. 7 is a fragmentary view in vertical section showing the trip member of the "no cap, no can" safety device.

Fig. 8 is a fragmentary view in section and elevation showing one of the cap feed fingers associated with a can accelerating arm.

Fig. 9 is a fragmentary view in section and elevation showing one of the accelerator arms and the manner in which it is propelled.

Fig. 10 is a fragmentary view in plan showing the means by which the accelerator arms are given a variable speed of movement.

Referring more particularly to the drawings 10 indicates a sub-frame carrying suitable bearings and supports for the various shafts and parts of the structure, it being understood that this sub-frame is disposed adjacent a can double seaming machine. A main vertical drive shaft 11 is suitably mounted in the sub-frame 10 and supported at its upper end by a bearing structure 12. This drive shaft is provided with a gear 13 acting through gears 14 and 15 to drive a stub shaft 16. The stub shaft is in turn connected to a secondary drive shaft 17 by gears 18 and 19. The secondary drive shaft 17 extends parallel to the shaft 11 and projects upwardly through supporting bearings 20. A sprocket 21 is secured to the secondary shaft 17 and acts through a sprocket chain 22 to drive a timing shaft 23. This timing shaft extends parallel to the shaft 17 and projects through a bearing 24. The shaft 23 carries a rotary can feed disk 25 onto which a flow of cans may be delivered.

Mounted above the disk and adapted to rotate with the same and the shaft is a star wheel 26. This star wheel is of peculiar configuration in that the teeth and the gullets between the teeth do not exactly fit the can, but represent an ogee curve of slight curvature, the curve forming a surface along which a can may roll as it rests upon the

disk 25, and as it is being advanced. Due to this action the can is permitted to gradually adjust its initial speed to the speed of the star wheel 26 so that it may be gradually 5 accelerated without jar or agitation.

The can is caused to roll as it successively engages arcuate retarding fingers 27 and 28. The finger 27 extends substantially one-third of the arc of the circumference of the 10 disk 25, while the finger 28 is of less length. Both of the fingers are mounted upon a common vertical pivot 29 and may swing horizontally as forced by the can. The fingers are yieldably held in the path of travel 15 of the can by compression springs 30 and 31. The spring 30 acts against the finger 27 and is of considerably greater strength than the spring 31 which acts against the finger 28. By reference to Fig. 2 it will be seen 20 that the portion of the finger 27 overlying the finger 28 is formed with a relieved face so that after the can contacts with the finger 27 and comes to a point of encountering finger 28 the can will be held by the lesser 25 pressure of the spring 31. Thus the retarding action of the can from the point of its encounter with the surface of the finger 27 to the point where it passes the pivot 29 of the two fingers will be gradually decreased, 30 permitting the friction of the disk 25 to gradually accelerate the speed of travel of the can and to cause the point 32 of a tooth of the star wheel 26 to overtake the can and carry it through the throat 33 into engagement with the initial can accelerating means 35 indicated generally at 34.

The initial can accelerating means comprises a rotary disk 35 fixed to the shaft 17 and a plurality of can timing and accelerating 40 fingers 36 mounted above the disk and carried by the shaft. The disk 35 is disposed directly beneath the disk 25 and thus the can in its transition from one disk to the other has an imperceptible fall represented 45 by thickness of the disk 25. The timing fingers 36 are formed as horizontally projecting parts of vertically extending levers 37. These levers are pivoted near their upper ends upon pins 38 and are disposed in slots 50 between combined bearings and guide members 39. The upper ends of the levers are fitted with rollers 40, as indicated in Fig. 2 of the drawings. These rollers project into an eccentric groove 41 of a cam 42. By 55 reference to Fig. 3 it will be seen that the groove is indicated in dotted lines and is eccentric to the shaft 17. It will also be evident that the eccentricity is such as to cause the fingers 36 to assume their inner- 60 most positions at the time they pass the point of delivery of the cans from the disk 25, and that they swing outwardly to an extreme position as the cans pass from the disk 35 and to other mechanism which will 65 be hereinafter described.

Due to this swinging action the fingers move radially and follow up the cans as they propel them along an eccentric course of travel off of the disk 35, as defined by an outer curved guide rail 43, and an inner 70 curved guide rail 44. The outer curved guide rail overhangs the disk 25 and the star wheel 26 and is formed at its end with a curved face or point 45 which is encountered by the can as it is projected forwardly 75 by the combined action of the disk 25 and the star wheel 26, and gradually moves the can out of engagement with the advancing tooth of the star wheel and into a position to be engaged by one of the accelerating 80 feed fingers 36.

During the course of travel of the cans while resting on the disk 35 they encounter a yieldable trip lever 46 which forms a part of a "no can, no cap" feed mechanism. 85 This mechanism will be described in detail hereinafter, and at the present time attention is merely directed to the fact that this member is mounted to swing horizontally on a shaft 47, and that it is of sufficient 90 length to be in simultaneous engagement with at least two cans during their travel with the disk 35.

The cans, upon leaving the disk 35, are fed into pockets 48 of can and cap accelerating members 49. These members are separately mounted upon the main drive shaft 11 and each constitute a horizontally swinging arm formed with the can receiving pocket 48 and a vertically swinging arm 50 carrying an upwardly projecting finger 51 adapted to engage and feed a can cap coincidentally with the can being seated in the pocket 48 of the same arm. The cap feeding finger 51 is more clearly shown in Fig. 100 8 of the drawings, where it will be seen to be in the shape of a bell crank mounted upon a shaft 52 and having an upwardly projecting arm carrying a roller 53. This roller is intended to extend into an eccentric cam groove 54 formed as a part of the fixed bearing structure 55 through which the shaft 11 extends. By reference to the dotted lines indicating the cam 54 in Fig. 110 3 of the drawing it will be seen that the finger 51 will be at its highest position as it passes beneath the cap feed mechanism generally indicated at 55, and that it will gradually lower in position until it reaches the station indicated at A, where it is intended that the can and cap associated therewith will be delivered coincidentally to the chucks of a double seaming spindle. 115

As previously stated, the arms 49 move independently of each other and are separately accelerated in a manner similar to that indicated in my copending application entitled Differential speed control can feed mechanism, Patent No. 1,581,201, issued April 20, 1926, in which patent the arms 120 125

are fitted with radially extending slide ways 56, as more particularly shown in Figs. 9 and 10 of the drawings. These ways carry blocks 57 mounted upon pins 58, which pins 5 in turn are carried on the links of a chain 59. The chain 59, as shown in Fig. 10, moves along an eccentric path of travel around the shaft 11 and an eccentric shoe 60, thus causing the pins 58 to assume positions at different distances from the axis of the shaft 11 and will thus cause the blocks 57 to move in and out along the ways 56 of the arms 49, so that a variable speed will be imparted to each arm individually during its cycle of travel. The structure is so designed that the speed of travel of each arm at the point where it receives a can from the can timing and accelerating mechanism 34 will be equal to the speed of the can received 10 and that the can will then continue in its progressive accelerated speed of travel.

The cap feed mechanism is of the reciprocating type, in which a pair of grooved members cuts the lowermost can from the 25 stack on the retracting stroke and projects the released can forwardly by movement of the pusher finger 62, as shown in Fig. 3 of the drawings. The caps are fed onto a supporting table 63 and as they project forwardly move into the path of travel of the can fingers 51 and fixed lugs 51' mounted on the accelerator arms 49. These members pass in through an arcuate slot 64 in the floor 63 and carry the cap forwardly above a 30 can which is thereafter delivered to the pocket of the arm 49 from the disk 35.

The foregoing sets forth the details of construction of the means for feeding, timing and accelerating the speeds of travel of 40 cans and caps. In addition to these structures two safety devices are provided, one being a so-called "no can, no cap" feed and the other being a "no cap, no can" feed. The "no can, no cap" feed has one particular 45 advantage in the present instance, in that it is actuated simultaneously by two cans, where heretofore these structures have always been independently actuated by each can, the result being that the interval of 50 actuation was so short, and the encounter of the trip mechanism by the can so violent, that the contents of the can was agitated and spilled. The present "no can, no cap" arrangement is intended to conform to the 55 general idea of the present invention in that it eliminates any tendency for the trip mechanism to jar the can. This structure is particularly shown in Figs. 1, 3 and 5 of the drawings, in which it will be seen that 60 the trip lever 46 is mounted on a shaft 47 and actuates a lever 65 disposed beneath the table. This lever is connected with a pitman rod 66 extending horizontally beneath the table and normally held in a retracted 65 position by a spring 67. The forward end

of this rod is connected to a bell crank 68 which projects outwardly and terminates in a finger 69 to engage the dog of a clutch 70 mounted on the shaft 71 of the can feed mechanism, and by which said mechanism 70 is actuated.

The "no cap, no can" mechanism actuates to discontinue the operation of the complete timing structure by throwing out the clutch of the drive pulley in the general manner 75 disclosed in my United States Letters Patent entitled Safety device for can machines, No. 1,545,140. In the present instance, however, a more positive actuating means for the safety device is provided, in 80 that it is fitted with a trip lever 71' which is supported upon pivots 72 for vertical swinging movement. This lever extends downwardly into the path of travel of the can caps as they are being fed forwardly 85 by the fingers 51 of the can accelerating arms 49. The lever 71' is positioned substantially in the middle of the path of travel of these caps so that the lever will wipe over the top 90 and the center of the caps and will thus be positively actuated for a prolonged period of time. This structure is more particularly shown in Figs. 3 and 6 and 7 of the drawings, where it will be seen that the upper 95 end of the lever 71' is provided with a connecting rod 73 extending horizontally to a swinging lever 74 mounted on a vertical shaft 75 at one side of the machine. The rod 75 extends downwardly to a point 100 beneath the machine, where it connects with a trip mechanism and from thence is connected by a pitman rod 77 with a catch pawl 78. This pawl may then be moved down to engage a notch in a ratchet 79 carried on the main drive shaft 11. The pawl 78 is 105 mounted on a lever 80 so that when it engages the ratchet 79 the clutch lever 81 will be actuated to pull on a clutch operating bar 82 and to thus pull the clutch out and render 110 the feed mechanism inoperative.

Having thus described my invention, what I claim and desire to secure by Letters Patent is:

1. A device for feeding cans and caps to a rotary turret high-speed double seaming machine, comprising a cap feed device means for timing cans with relation to each other and carrying them through the feeding device and to the double seaming machine at a gradually accelerated rate of speed while 115 passing the cap feed device, and automatically operated means in the path of travel of the cans separately and successively operated by the traveling cans causing actuation of the cap feed device when engaged by 120 a can.

2. A device of the character described, 125 can timing and spacing means comprising a rotary disk onto which cans are delivered while standing in a vertical position there- 130

- on, means above the disk and moving therewith with which the cans come into engagement and by which they are carried forwardly, and means arranged around the 5 disk and along the path of travel of the cans for successively retarding the travel of the individual cans until they have been engaged by the positive advancing means.
3. In a device of the character described, 10 a horizontal continuously rotating disk onto which cans are successively fed and by which they are carried forwardly while in frictional engagement therewith, positive advancing means for engaging the separate 15 cans and carrying them forwardly while resting on the disk, and means for gradually and successively retarding the cans until they have become engaged by the positive advancing means.
- 20 4. In a device of the character described, a horizontally disposed continuously rotating disk onto which cans are delivered from a run of cans in an upright position, and by which said cans are carried forwardly 25 with the disk while in frictional engagement therewith, positive can feed means disposed above the disk and rotating therewith, and with which the can becomes engaged at certain points on the disk, and means defining 30 the path of travel of the cans on the disk, said means including means for gradually retarding the speed of travel of a can in engagement therewith until it has become engaged by one of said positive feed means.
- 35 5. In a device of the character described, a horizontally disposed continuously rotating disk onto which cans are delivered from a run of cans in an upright position, and by which said cans are carried forwardly with 40 the disk while in frictional engagement therewith, positive can feed means disposed above the disk and rotating therewith, and with which the can becomes engaged at certain points on the disk, means defining the 45 path of travel of the cans on the disk, said means including means for gradually retarding the speed of travel of a can in engagement therewith until it has become engaged by one of said positive feed means, and means for carrying the successive cans from 50 said disk and conveying them forwardly to a continuous rotary turret double seaming machine at gradually accelerating rates of speed.
- 55 6. A device of the character described comprising can spacing and timing means, means for separately engaging the consecutive cans and carrying them forwardly from the timing means at gradually accelerated 60 rates of speed, means for receiving a can cap and carrying it forwardly at a gradually accelerated rate of speed to a continuously rotating turret double seaming machine, and means whereby the cans advancing 65 from the can timing means at gradually

accelerated rates of speed will be successively delivered to the means advancing the caps at an increased accelerated rate of speed whereby a can and cap will advance together to the double seaming turret.

7. A device of the character described comprising can spacing and timing means, means for separately engaging the consecutive cans and carrying them forwardly from the timing means at gradually accelerated 70 rates of speed, means for receiving a can cap and carrying it forwardly at a gradually accelerated rate of speed to a continuously rotating turret double seaming machine, means whereby the cans advancing from the can timing means at gradually accelerated 75 rates of speed will be successively delivered to the means advancing the caps at an increased accelerated rate of speed whereby a can and cap will advance together to the double seaming turret, and means automatically actuated by the delivery of a can to said can and cap feeding means whereby a cap will be fed to the can.

8. A device for timing and feeding cans 80 and carrying them to a high speed rotary double seaming machine from a relatively slow flow of cans, comprising means for initially spacing successive cans equidistant to each other as they continue to travel, a series 85 of members individually operating to engage successive cans and to carry them forwardly toward the double seaming machine at a gradually accelerated rate of speed, a series of individual can and cap receiving 90 members for receiving the cans travelling at the accelerated rate of speed, and further gradually accelerating the speed of travel of the cans while delivering them to the double seaming turret.

9. A device for timing and feeding cans and carrying them to a high speed rotary double seaming machine from a relatively slow flow of cans, comprising means for initially spacing successive cans equidistant to 100 each other as they continue to travel, a series of members individually operating to engage successive cans and to carry them forwardly toward the double seaming machine at a gradually accelerated rate of speed, a series of individual can and cap receiving 105 members for receiving the cans travelling at the accelerated rate of speed, and further gradually accelerating the speed of travel of the cans while delivering them to the double seaming turret, and means for delivering caps to the respective can receiving and accelerating means to be carried forwardly therewith.

10. A device for timing and feeding cans 125 and carrying them to a high speed rotary double seaming machine from a relatively slow flow of cans, comprising means for initially spacing successive cans equidistant to each other as they continue to travel, a series 130

of members individually operating to engage successive cans and to carry them forwardly toward the double seaming machine at a gradually accelerated rate of speed, a 5 series of individual can and cap receiving members for receiving the cans travelling at the accelerated rate of speed, and further gradually accelerating the speed of travel of the cans while delivering them to the 10 double seaming turret, means for delivering caps to the respective can receiving and accelerating means to be carried forwardly therewith, and automatic means influenced by each can at a point in its travel for setting the cap feed mechanism in motion for 15 the delivery of one cap to a can receiving member.

11. A device for timing and feeding cans and carrying them to a high-speed rotary 20 double-seaming machine from a relatively slow flow of cans, comprising means for ini-

tially spacing successive cans equidistant to each other as they continue to travel, a series of members individually operating to engage successive cans and to carry them forwardly toward the double-seaming machine at a gradually accelerated rate of speed, a 25 series of individual can and cap receiving members for receiving the cans traveling at the accelerated rate of speed, and further gradually accelerating the speed of travel of the cans while delivering them to the double-seaming turret, means for delivering caps to the respective can receiving and accelerating means to be carried forwardly 30 therewith, and means in the path of travel of the cans whereby the presence of a can at a point in its travel will cause the entire feed means to remain operative but the absence of a can at said point will render the 35 structure inoperative.

HENRY L. GUENTHER.
